RECTIFIER TUBE

Johannes Bruijnes, Mount Vernon, N. Y., and Daniel Marie Duinker and Johannes Gijbertus Wilhelm Mulder, Eindhoven, Netherlands, assignors to N. V. Philips' Gloeilampenfabrieken, Eindhoven, Netherlands

Original application August 6, 1934, Serial No. 738,758. Divided and this application January 17, 1938, Serial No. 185,456. In Germany August 7, 1933

2 Claims. (Cl. 250—27.5)

The present invention which is a division of our copending U. S. patent application Ser. No. 738,758, filed August 6, 1934, relates to incandescent-cathode, gas-filled rectifier tubes, and more particularly to tubes for rectifying alternating current of medium voltages, i. e., voltages having a peak value of about 250 volts to about 1000 volts and higher, and for current of several amperes up to 100 amps. and higher.

10 Although incandescent-cathode gas-filled rectifier tubes have been widely used for various applications and for various voltages, commercially successful tubes of this type could be made for only two voltage ranges, namely, for low voltages up to about 150 volts, and for high voltages above about 1000 volts, whereas for intermediate voltages no satisfactory tubes of this type could be made. The reasons therefor will be explained below.

20 In designing commercial rectifier tubes the following main three factors must be considered. The tube must have a satisfactory long life, i. e. of the order of one thousand hours and more; must have a high efficiency, i. e., a low internal voltage-drop as compared to the voltage of the alternating current source to be rectified; and no back discharge should occur in operation, i. e., the tube must withstand the highest inverse voltage which may occur across its electrodes during operation.

30 For low voltages there is no difficulty in providing a tube which meets the above requirements. To provide a low voltage drop, the gaseous filling of such tubes consists solely or mainly of an inert gas, for instance of argon, and the pressure of the gas filling can be quite high without danger of breakdown or back discharge, usually of the order of several mms. and up to several cm. of mercury. Such a high pressure gas filling protects the electrodes from disintegration, and makes a low internal voltage drop of the tube possible, which results in a high efficiency.

40 While the high pressure gas filling is no drawback as long as the voltage to be rectified has a low value, if the tube is to stand higher voltages the pressure of the gaseous filling has to be reduced. This, in the case of tubes having an inert gas filling, results in an objectionable phenomenon, namely, the gradual disappearance of the gas filling which is due to the disintegration of the electrodes, especially of the cathode. This disintegration increases with increasing voltages and decreasing gas pressures, whereby the disintegrated particles of the electrodes occlude the gas

metal parts of the tube. Such disappearance of the gas filling not only lowers the efficiency of the tubes, but further reduces the protective action of the gas filling. This in turn further increases the rate at which the disintegration of the electrodes takes place and still further accelerates the disappearance of gas. The result is that the usefulness of such a tube is destroyed in a comparatively short time.

5 In low-voltage tubes, the disintegration of the electrodes, because of the low voltages and the protective action of the high pressure gas filling, is small and the rate of the disappearance of the gas is slow. Also, because of the high pressure of the gas filling, and thus the large quantity of gas in the tube, the amount of gas which becomes occluded by the disintegrated particles is only a small part of the initial gas filling of the tube. Thus, while in low-voltage, high-gas-pressure tubes the disappearance of the gas filling 10 is negligible, in higher-voltage, low-gas-pressure tubes this phenomenon has been detrimental to the tube. It has been found furthermore that as long as the initial pressure of the gas filling 15 is of the order of several mm. of Hg., the disappearance of the gas during the normal life of the tube is not fatal to the tube; however, with initial gas pressures below a few millimeters the disappearance of the gas materially reduces the 20 life of the tube.

25 To avoid the disappearance of the gaseous filling in tubes operating on voltages which require gas pressures below a millimeter to prevent breakdown of the tube, mercury vapor has been resorted to as the gaseous filling of the tube, where- 30 by an excess of mercury, in liquid form, is provided in the tube; the liquid mercury serving as a reservoir to replace the mercury which disappears because of its occlusion by the disintegrated particles of the electrodes.

35 The required pressure of the saturated mercury vapor in the tube is obtained by the proper temperature of the mercury, which in turn, as is known, is obtained by the proper relative location of the mercury, the incandescent cathode, 40 and the discharge path. For instance, to reduce the pressure of the mercury vapor the liquid mercury is spaced at a greater distance from the heat sources (cathode and discharge space) and vice versa.

45 The pressure of the mercury vapor used in such high voltage tubes being low, and also because of the use of mercury vapor instead of inert gas, the internal resistance of such tubes and their 50 voltage drop is high. This is no serious objection 55

in a tube designed for quite high voltages, for instance, for voltages above 1000 volts, as the internal voltage drop in percentage of the voltage of the alternating current source is not excessive, 5 and also because these tubes are usually designed for small currents, whereby the loss in the tube is not a serious matter.

However, for the intermediate voltages with 10 which the present invention is concerned, namely, above a peak voltage of about 250 volts and up to about 1000 volts, the high voltage drop in the tube is highly objectionable, especially if the tube is for large currents, as this results in a large internal energy loss and a large amount of heat 15 developed in the tube. If such tubes for intermediate voltages are filled only with an inert gas, the disappearance of the gas filling—because of its initially low pressure—would result in a rapid deterioration of the tube.

20 On the other hand, low-pressure mercury vapor, as stated provides for too high a voltage drop, and if the pressure of mercury vapor is increased to about a millimeter or several millimeters, back discharge is likely to occur and at 25 the same time the pressure of mercury at higher pressures is quite sensitive to temperature variations caused, for instance, by changes in ambient temperature. Thus a rectifier having a gaseous filling consisting solely of mercury vapor 30 at a pressure of the order of several millimeters, is likely to be unstable in operation.

Because of the above difficulties, prior to the 35 present application gas-filled incandescent cathode rectifier tubes were not commercially available for rectifying alternating voltages of about 250 volts to about 1000 volts (peak values) except in cases of certain special applications where the high voltage drop of the tube was of no consequence.

40 In an endeavor to provide such tubes, for which there is evidently a great demand for various purposes, it has already been proposed to use a reservoir of liquid mercury for maintaining a constant mercury vapor pressure, and at the 45 same time, to reduce the voltage drop of the tube and stabilize the pressure by adding an amount of inert gas of such a pressure as has been found necessary to avoid the disappearance of the gas. However, such tubes which contained mercury 50 vapor and an inert gas, for instance argon, of a pressure of several millimeters, when used for rectifying alternating voltages of a peak value of 250 volts or more, did not give satisfactory results.

This was due to the fact, that in such tubes, 55 under the usual conditions of operation, back discharges could not be avoided. In the operation of such tubes for rectifying alternating currents of a peak value of about 250 volts, voltages much higher than 250 volts can occur. For instance, when using a single three-phase rectifier 60 for rectifying three-phase alternating current having an effective phase voltage of 220 volts and a phase peak voltage slightly above 300 volts, a peak voltage of 537 volts will occur between the 65 anodes, and we have found that under certain conditions a value double this voltage may occur in the tube. The difficulty is further increased if the rectifier is used for the rectification of currents of substantial value, especially in the case 70 of the high efficiency oxide cathode tubes. In such case because of the large currents, the anode assumes a comparatively high temperature and part of the electron-emitting material, for instance barium oxide, which is disintegrated from 75 the cathode, deposits on the anodes and causes

a marked electron emission of the same to thereby promote back discharge. Even if initially the rectifier tubes might operate satisfactorily under such conditions, back discharge will set in after awhile.

Thus the problem of devising satisfactory gas-filled incandescent cathode rectifier tubes for medium voltages remained unsolved.

Applicants have found the very surprising phenomenon that in the presence of mercury vapor 10 a much smaller quantity of inert gas, or in other words, an inert gas filling of much lower pressure, can be preserved within the tube than has been assumed heretofore. Thus, while argon disappears from the tube, if used alone at a pressure 15 of 1 millimeter, when argon is used in the presence of mercury vapor it does not disappear from the tube, even if the initial pressure of the argon is of the order of tenths or hundredths of millimeters. We do not know the exact reason for 20 such behavior, but believe that a protective action by the mercury-vapor takes place, the indications being that the disintegrating particles of the electrodes occlude only mercury vapor, instead of occluding both the mercury vapor and 25 the inert gas.

More particularly we have found that gas-filled rectifier tubes having a gaseous filling comprising an inert gas, preferably argon or neon at a pressure of between 0.01 and 0.5 mm. of Hg in 30 the case of argon, and from 0.02 to 1 mm. of Hg in the case of neon, together with saturated mercury vapor—the pressure of the mercury vapor being preferably the same order of magnitude as the pressure of the inert gas—will retain their 35 initial gas pressure in operation. Especially tubes comprising argon at a pressure of 0.2 to 0.4 or neon at a pressure of 0.3 to 0.8 mm. of Hg, give an all-round satisfactory performance at medium voltages. More particularly the disintegration of 40 the electrodes is prevented, the tubes have a satisfactory life and efficiency and the danger of back discharge is overcome.

To prevent formation of amalgam, due to the presence of mercury, the anodes of such tubes 45 are made of or provided with a surface coating of a material which does not form an amalgam with mercury. Preferably the anodes are made of polished graphite, of metal coated with graphite, or a chromium or chromium oxide 50 coating may be used.

To prevent back discharge, further measures are also taken. For instance the supports and lead wires may be air-tightly enclosed with refractory insulating material, for instance, with 55 steatite. The cathode may also be partly enclosed by a shield to eliminate or at least minimize the deposition on the anode of disintegrating cathode particles.

In order that the invention may be more 60 clearly understood and readily carried into effect we shall describe same in more detail with reference to the accompanying drawing in which,

Figure 1 is a side view partly in section, of a 65 three-phase rectifier tube embodying the invention, and

Fig. 2 is a section along line 2—2 of Fig. 1.

The rectifier tube illustrated in Figures 1 and 2 is designed for the rectification of a three-phase 70 alternating current having an effective phase voltage of 220 volts, and thus a peak voltage somewhat above 300 volts. The illustrated tube is designed for currents of about 6 amperes and is shown in reduced scale, the length of the con- 75

tainer tube being about 7" and its diameter being about 3 3/4".

The tube comprises a container 1 of vitreous material. Disposed within the container and 5 slightly below the center thereof, is a filamentary cathode 2, preferably an oxide cathode, provided with a suitable oxide coating of high electron emissive properties such as a barium oxide coating.

10 Cathode 2 is supported by supports 4 and 3, which are secured, preferably welded to chrome-iron discs 5, to the outer face of which discs are welded lead wires 6, the chrome iron discs being air-tightly fused to the glass.

15 Surrounding cathode 2 is an open-ended cylindrical screen 7, which may be electrically connected to one end of the cathode, for instance by a conductor 8 connecting screen 7 with support 4. The screen has among others the advantage 20 of reducing the danger of disintegrating cathode particles reaching the anodes and the glass wall of the tube.

25 Arranged above cathode 2 are three anodes 9, 10 and 11 of similar construction, each being connected to a conductive rod 12, which may be threaded at its end and screwed into the anode, as shown at 13. Anode rod 12 is surrounded by a suitable insulating tube 14, for instance of steatite, which at its upper end 15 is sealed to a 30 glass tube 16 which preferably forms an integral extension of the glass wall of container 1.

35 Rod 12 has its upper end welded to the inner face of a chrome-iron disc 17, which is fused into container 1. Secured to the outer face of chrome-iron disc 17 is a terminal connection 29 for the anode 11, which is electrically connected thereto through rod 12 and chrome-iron disc 17.

40 The anode is provided on its upper portion with an annular bore 18, which extends inwardly into an annular bore 19 of slightly smaller diameter. The lower end of insulating tube 14 snugly fits into bore 19, whereby rod 12 is protectedly enclosed by the tubes 14 and 16. At the same time the annular gap formed around tube 45 14 at bore 18 offers a narrow high-resistant path between the contacting point of tube 14 with the anode and the discharge space. This provision reduces the danger of a glow-discharge being formed at said point.

50 Surrounding anodes 9, 10 and 11 is a cylindrical housing 20, which is closed at the top and open at the bottom. The space within housing 20 is subdivided into three parts by three radial and preferably imperforated partition walls 21 (see Fig. 2), each part housing one of the anodes. Opposite the central portions of the anodes the wall of housing 20 is broken away and replaced by metal gauze screens 22, 23 and 24 respectively. Such arrangement permits the discharge to take 55 place between the cathode and the anode not only through the open bottom of housing 20, but also through the gauze 22, 23 and 24, the latter also facilitating the heat dissipation of the anodes. On the other hand the non-perforated 60 partitions 21 and the non-perforated portions of

the housing 20, effectively prevent a discharge between the anodes.

If desired, a suitable potential may be applied to housing 20 by connecting the same to a suitable potential by means of a wire 25 hermetically led through the container wall at 26.

A mica disc 27 provided in the upper portion of the tube, serves to protect the seals from being excessively heated from the discharge space.

It will be noted that the anodes have a sector-shaped cross-section so as to more completely fill the space formed within housing 20. As stated, we prefer to make the anodes of graphite, which is preferably polished on its surface opposing the cathode, or to provide a metal anode 15 which is coated with either graphite or with another substance which does not produce an amalgam with mercury, as chromium or chromium oxide.

20 The gaseous filling of the tube may consist, for instance of neon at a pressure of 0.5 mm. of Hg; a drop of liquid mercury 28 being provided for the generation of mercury vapor, preferably at a pressure of the same order of magnitude as the neon. The desired mercury vapor pressure 25 is obtained by the mercury assuming in operation the temperature giving this pressure, which as is known, can be obtained by the proper disposition of the liquid mercury with regard to the cathode and the discharge.

30 While we have described our invention in connection with specific applications and embodiments, we do not wish to be limited thereto but desire the appended claims to be construed as broadly as permissible in view of the prior art.

What we claim is:

1. A rectifier tube for rectifying alternating voltages of a peak value of at least 250 volts comprising, an envelope, an incandescent cathode, a cylindrical-shaped screen of conductive material 40 forming a plurality of cavities having sector-shaped cross sections, an anode within each of said cavities and having a sector-shaped cross-section, said screen separating said anodes from each other and substantially enclosing each 45 anode while allowing access of the main discharge thereto, and a gaseous filling comprising saturated mercury and an inert gas.

2. A rectifier tube for rectifying alternating voltages of a peak value of at least 250 volts comprising, an envelope, an incandescent cathode, a screen of conductive material provided with a plurality of cavities each having an opening toward said cathode and an opening at the peripheral surface of the screen, a metallic network 50 covering said latter opening, an anode within each of said cavities, said screen separating said anodes from each other while allowing access of the main discharge thereto, and a gaseous filling comprising an inert gas and saturated mercury 55

60 vapor.
